SLIDE FASTENER CONSTRUCTION

Isaac Marinsky, Providence, R. I.

Application July 13, 1942, Serial No. 450,664

2 Claims. (Cl. 24—205)

The present invention relates to improved zipper constructions, and has particular reference to concealed closure arrangements.

The principal object of the invention is to provide a concealed closure arrangement for a separable slide fastener, of simple and inexpensive construction.

Another object of the invention is to provide a novel tape assembly for mounting the separable fastener elements.

Still another object is to provide improved slider constructions for the concealed closure arrangements.

With the above and other objects and advantageous features in view, the invention consists of novel arrangements of parts, more fully disclosed in the detailed description following, in conjunction with the accompanying drawings, and more specifically defined in the claims appended thereto.

In the drawings,

Fig. 1 is a plan view of a preferred embodiment of the invention, parts being broken away.

Fig. 2 is a rear view thereof.

Fig. 3 is a section on the line 3—3 of Fig. 2.

Fig. 4 is a plan view of a novel tape.

Fig. 5 is a section on the line 5—5 of Fig. 4.

Figs. 6 and 7 are diagrammatic views showing the steps of weaving the novel tape.

Fig. 8 is a section showing the assembly of the zipper elements on the tape.

Fig. 9 is a perspective view of the slider for the embodiment of Fig. 1.

Fig. 10 is a plan view, similar to Fig. 1 of another form of the invention.

Fig. 11 is a rear view of Fig. 10.

Fig. 12 is a section on the line 12—12 of Fig. 10.

Fig. 13 is a plan view, partly broken away, of still another embodiment.

Fig. 14 is a rear view of Fig. 13, the rear flap being turned.

Fig. 15 is a section on the line 15—15 of Fig. 13, and

Fig. 16 is a perspective of the slider for the embodiment of Fig. 13.

Referring to Figs. 1 to 3 of the drawings, the preferred zipper construction is designated 10, and includes two complementary series 14 and 15 of slide fastener elements, the series being mounted on tape elements 11 and 12, a slider 16 serving to selectively seal and open the slide fastener elements by manual reciprocation.

As more clearly shown in Fig. 3, each tape element has an overlap section 17, the two sections overlapping in superimposed relation to com-

pletely conceal the closure parts. This desirable result is obtained by providing a novel tape design, illustrated in Figs. 4 to 8, the tape 18 having a relatively large bead 19 of textile or other suitable material woven as an integral part thereof, in spaced adjacency to the tape edge. The preferred weave is shown in Figs. 6 and 7, the warp being alternately woven into the tape and then around the bead, whereby every alternate warp 10 weave serves as a lock for the bead. With this construction, the tape 18 has the bead 19 extending entirely from one face thereof, the other face being plane, and the overlap section 17, see Figs. 5 and 8, is readily bent back to permit clamping 15 assembly of the individual fastener elements 13 thereon.

The tape sections 11 and 12, constructed as illustrated in Fig. 8, when assembled as shown in Figs. 1, 2 and 3, completely conceal the closure parts, and the depending fastener elements permit the use of a special slider 16, see Fig. 9, which has a front plate 20, a rear plate 21 in spaced relation thereto, a spreader bar 22, and a tab 23, the tab 23 being swivelly mounted on the rear 20 plate, which has two side flanges 24, 25 to ride over the upwardly extending sides of the closure elements. The tapering formation of the plate 20 permits a smooth closing of the two overlap sections 17 when the zipper is closed.

If desired, the overlap sections may be made of a width to abut, as shown in Figs. 10 to 12, wherein the slide fastener assembly 26 has two tape assemblies 27, 28 provided with complementary series of slide fastener elements 29, 30, and 35 a slider 31, the tape assemblies respectively having overlaps 32, 33 which abut when the fastener elements are in closed position. With this construction the slider 31 is of conventional form at the back, but the front plate 34 is cut away at the sides to a width less than the width of the two abutting overlap sections, whereby the front plate is always beneath the overlap sections and does not bend or twist the overlap sections when the zipper is opened.

The novel tape design readily lends itself to other zipper assembly arrangements. Thus, referring to Figs. 13 to 15, the assembly 35 uses two tapes 36, 37, provided with fastener elements 38, 39 and a slide 40, the tapes having overlap sections 41, 42 which are positioned on opposite sides of the fastener elements, see Fig. 15, so as to completely conceal both sides. With this arrangement, the slider 40 includes a back plate 43 having side flanges 44, 45 to engage the bottom portions of the fastener elements, a separating

or spreader bar 46, and a front plate 47 which is bent in the form of a U to embrace the upper overlap section 41, and is provided at the side with a depending flange 48 to ride over the inner edge of the overlap section, this inner edge being slightly raised by the fastener elements. A tab 49 is attached to a tab support 49a on the upper portion of the front plate 47.

The slider 40 thus includes two plate elements that slide over the fastener elements and act as slide housings for the overlap sections, thus continually aligning the overlap sections to keep the fastener elements concealed.

While I have described specific constructional embodiments of my invention, it is obvious that changes in the size, shape, and arrangements of the parts may be made to suit different slide fastener requirements, without departing from the spirit and the scope of the invention as defined in the appended claims.

I claim:

1. A slider for a slide fastener assembly, having a bottom plate member with upwardly directed side flanges, a top plate member of U-shape hav-

ing upper and lower spaced parallel portions, and a spreader bar positioned between said plate members, one of said portions having a side flange extending towards the other portion, said top plate upper portion having a pull tab support.

2. A slide fastener comprising a pair of tape assemblies each having a bead extending from one surface in parallel relation to the margin thereof to provide a tape body and an overlap section, a series of cooperating slide fastener elements mounted on said beads, one overlap section extending over the upper surfaces of said series of fastener elements and the other overlap section extending over the lower surfaces thereof, and a slider device cooperating with said fastener elements to open and close the fastener, said slider element having spaced upper and lower plates and a spreader bar, said plates being respectively positioned between the fastener elements and the overlap sections, the upper plate having an auxiliary plate portion which extends over the upper overlap section, said auxiliary plate portion having a pull tab support.

ISAAC MARINSKY.
